INVENTOR,
Marinus Pepling.

John Seward.
ATTORNEY

UNITED STATES PATENT OFFICE.

MARINUS PEPLING, OF PATERSON, NEW JERSEY.

FELL-FINDING MEANS FOR LOOMS.

Application filed October 6, 1923. Serial No. 666,918.

To all whom it may concern:

Be it known that I, MARINUS PEPLING, a citizen of the United States, residing at Paterson, in the county of Passaic and State of New Jersey, have invented certain new and useful Improvements in Fell-Finding Means for Looms, of which the following is a specification.

This invention relates to means for determining in weaving the position of the fell of the cloth with reference to the true fell line, as when the sheet of cloth and warp has to undergo a setting back in the loom following the ravelling out of some of the picks of weft due to some fault in the weaving. When any such setting back of the sheet of cloth and warp is effected at present it is very difficult to "join" properly, the first one or more picks after the weaving is resumed having a too crowded or too much spaced arrangement in the cloth due to the sheet not having been set back with the new fell accurately in register with the true fell line.

My invention aims principally to overcome this difficulty by providing the loom with means whereby to stop the backward movement of the take-up means, on shifting the sheet of cloth and warp backward, immediately upon the new fell registering with the true fell line. In the specific form of the invention herein set forth by way of example the actual stopping means embodies the usual holding pawl for the take-up means and when the sheet of cloth and warp is to be set back this stopping means is shifted clear of the take-up means and held in the retracted position by detent means which then stands projecting into the shed of the warp in the path of rearward movement of the new fell, so that when the setting back of said sheet occurs the detent means will be shifted, tripping the stopping means so that it reengages the take-up means and stops its rearward movement (rotation).

In the drawings,

Fig. 1 is a side elevation of a loom embodying my invention;

Fig. 2 is a plan of the breast beam of the loom, the sheet of cloth and warp and certain of the parts of my invention;

Figs. 3 and 4 are sections on lines 3—3 and 4, Fig. 2;

Fig. 5 is a plan of certain parts; and

Fig. 6 is a side elevation of those parts of my mechanism which are mounted on the breast-beam.

In the loom-frame *a* are arranged the following well-known parts: the let-off or warp beam *b* journaled in the frame and having the coil of a rope *c* around one end thereof, the forward end of the rope carrying the weight *c'* and the rearward end the heavier weight *c''* so that the sheet of cloth and warp is subject to a constant rearward pull and occasionally, as the sheet of cloth and warp is advanced, the weight *c'* touches the floor and so brings about the let-off or forward rotary motion or slip of the beam *b*; the whip-roll *d* and breast-beam *d'* over which the sheet of cloth *A* and warp *B* is stretched; the take-up or cloth beam *e* connected by gearing *f* with the pick or ratchet wheel *g*, which may be advanced step by step by the lever *h* actuated from some reciprocating part (not shown) of the loom and having a pawl *h'* (shown disengaged in Fig. 1) to engage the teeth of said wheel; the batten-including structure *i* reciprocated from the crank shaft *j* through the pitmen *k*; and the harness *l* for forming the sheds *C* in the warp. *m* is the usual holding pawl for the ratchet wheel, pivoted in the frame.

On the back of the breast-beam are fixed two brackets *n*, suitably spaced from each other horizontally. In these is fixed a shaft *o* square in cross-section, and journaled in the brackets, rearward of this shaft, is another shaft *p*, also square in cross-section. The latter shaft is kept from endwise movement by having its inner end reduced to form a shoulder abutting the inner bracket and carrying a fixed collar *q* which abuts the outer bracket. At its outer end shaft *p* has affixed thereto, by a set-screw *r*, a crank *s* which is connected to the pawl *m* by the link *t*. A fairly strong spring *u*, coiled about shaft *p* and engaged at one end with a collar *v* thereon and at the other end with the outer bracket, tends to turn the shaft in the direction to depress the crank and therefore the pawl so as to hold the latter engaged with the teeth of the ratchet-wheel. The shaft *p* also carries an arm *w* projecting upwardly; this arm has a square hole through which the shaft extends, so that while the arm is fixed to turn with the shaft it may slide longitudinally thereon,

being in effect splined to the shaft. In the free end of this arm is a hole w' penetrating it at right angles to the shaft and receiving a pin x which protrudes at the sides of the 5 arm adjacent the breast-beam and may yield therefrom against the tension of a light spring y .

On the shaft o is arranged to slide lengthwise thereof a bracket z which has a fork z' 10 between the members of which the arm w is arranged, so that when the bracket is shifted the arm travels with it. The bracket is kept from turning on the shaft, or in the upright position shown in Fig. 4, 15 by having a square hole receiving and fitting it, as shown in said figure, and when it has been shifted to any position on the shaft it may be there held by a set-screw 2. In the body portion and an overhang z^2 of the 20 bracket is journaled a vertical spindle 3 on which is fixed an ovoid arm 4 which, when the spindle is turned counter-clockwise as viewed in Fig. 2, acts as a cam, its pointed or free end then wiping against the arm w 25 (then held by spring u in the position of Fig. 4) and camming it aside and incidentally camming back the pin x . The spindle is normally turned in the clockwise direction in Fig. 2 by a spring 5 having its end 30 engaged with the arm 4 and bracket z , being coiled about the spindle.

On the upper end of the spindle is an arm preferably formed in two parts, as follows: The part 6 is fixed to the spindle and has 35 an opening 6^a therein and a longitudinal slot 6^b . The part 7 has its outer end turned off obliquely (toward the sheet of cloth and warp), as at 7^a , and its inner end 7^b threaded and equipped with a nut 8; it is journaled in lugs 6^c depending from part 6 and has its nut 8 received in and fitting the opening 6^a , so that a micrometer adjustment of the part 7 lengthwise of part 6 is afforded. 9 is a set-screw, tapped into part 7 and 40 penetrating slot 6^b , for securing part 7 rigidly to part 6 when the adjustment has been effected.

The device is used as follows: The normal 45 position of the detector or detent means constituted by the spindle and its two arms is that shown by dotted lines in Fig. 2, in which position it is held by the spring 5. At this time this member, the detector, is clear of the arm w so that the pawl is engaged with the ratchet wheel and so holds the take-up means against re-rotation each 55 time it is advanced by the pawl h' . In order on shifting back the sheet of cloth and warp for any purpose (as when there has been a fault in the weaving necessitating the ravelling out of some of the weft) to bring the (new) fell to the true fell line, the weaver first swings the detector to the 60 full-line position in Fig. 2. In this the arm w is cammed, as explained, away from the

breast-beam, resulting in clearing pawl m from the ratchet wheel, the detector being now retained in this position (holding the pawl m as stated) by pin x , as shown in Fig. 5, and its oblique end 7^a projecting into the shed C back of the fell. The weaver now lets back the sheet of cloth and warp, as by having first disengaged the pawl h' from the ratchet wheel, and immediately upon the fell of the cloth engaging and so moving the detector the latter presses back and so clears pin x and swinging to its normal position under the impulse of spring 5 releases arm w and consequently the pawl m , which re-engages the ratchet wheel and so stops any further letting back of said sheet. The part 7 is adjusted, of course, so as to be adapted to bring about the tripping of the arm w , pawl m and the connections between them, when the detector is in the position of Fig. 2.

A light spring y is employed so that the slightest pressure of the cloth against the detector will suffice to cause the tripping. On the other hand, a stronger spring u is employed so that when the detector releases the stopping means the latter will act instantaneously to engage and stop the backward rotation of the cloth-beam.

The bracket z with arm w and those of the parts that are carried by the bracket, are shiftable lengthwise of the shafts o p so as to be adapted to any width of fabric.

So far as I am aware it is not only new to utilize the sheet of warp and cloth to control means for stopping its shifting backward but it is also new to cause said sheet in the shifting thereof to effect release of an element, such as the detector adapted to be thrown to a definite position and thereby indicate that in the shifting said sheet has assumed a predetermined position. It is also new to provide a system of parts including means to hold the take-up means against backward movement and a fell-gaging means (the end 7^a of detector 7 serving as the gage) movable into and out of gaging relation to the fell of the cloth.

Having thus fully described my invention, what I claim and desire to secure by Letters Patent is:

1. In a loom, the combination of mechanism to maintain the sheet of warp and cloth taut and shift the same forward or backward, said mechanism including a forward-and-backward-movable take-up means for the cloth, and means, having a movable controlling part arranged rearward of and adapted to be actuated by the fell of the cloth, to stop the backward movement of the take-up means on shifting the sheet backward.

2. In a loom, the combination of mechanism to maintain the sheet of warp and cloth taut and shift the same forward or back-

- ward, said mechanism including a forward-and-backward-movable take-up means for the cloth, means to form a shed in the warp, and means, having a movable controlling part projecting laterally into the shed and adapted to be actuated by the forward part thereof, to stop the backward movement of the take-up means on shifting the sheet backward.
3. In a loom, the combination of mechanism to maintain the sheet of warp and cloth taut and shift the same forward or backward, and indicator means normally urged to a definite position, and means to releasably hold said indicator means out of said
- position, the sheet on being shifted being adapted to engage and release the indicator means from the holding means.
4. In a loom, the combination of mechanism to maintain the sheet of warp and cloth taut and shift the same forward or backward, said mechanism including a forward-and-backward-movable take-up means for the cloth, and a movable system of parts including means to hold the take-up means against backward movement and a fell-gaging means movable into and out of gaging relation to the fell of the cloth.

In testimony whereof I affix my signature.
MARINUS PEPLING.
